UNITED STATES PATENT OFFICE.

JOHN M. HOPWOOD, OF DORMONT, PENNSYLVANIA.

CONTROLLING COMBUSTION BY FLOW AND PRESSURE.

1,338,925.

Specification of Letters Patent.

Patented May 4, 1920.

Application filed September 20, 1918. Serial No. 254,977.

To all whom it may concern:

Be it known that I, JOHN M. Hopwood, residing at Dormont, in the county of Allegheny and State of Pennsylvania, a citizen 5 of the United States, have invented or discovered certain new and useful Improvements in Controlling Combustion by Flow and Pressure, of which improvements the following is a specification.

10 The invention described herein relates to a method of controlling combustion of fuel for the generation of steam or other gaseous product and consists generally stated in maintaining the products of combustion in 15 the furnace of the generator under a suitable pressure by regulating the discharge of such products by and in accordance with changes in the components of the total pressure of the steam or vapor flowing from the generator, *i. e.*, with changes in the rate of flow 20 of the generated product as steam from the generator and the variations from normal of the static pressure of such products in the generator, and also regulating the feed of 25 fuel, the supply of air for combustion being proportional to the rate of discharge of products of combustion.

This method is well adapted to use where 30 single unit boiler control is desirable and where gaseous or liquid fuels are employed. This method presents decided advantages in 35 simplicity of equipment and generally satisfactory results in practice. By calibrating the air duct damper when employing forced draft to conform to the setting of the stack damper, a predetermined furnace pressure or condition may be established, dependent 40 upon the rating, and with the use of a fairly uniform grade and size of fuel may be successfully maintained under ordinary load variations. The fuel feed, the air supply and the escape of the products of combustion are each and all instantly and simultaneously controlled by and in accordance 45 with flow and pressure variation in the steam outlet of each individual boiler. These incremental adjustments of the stack damper, air supply and fuel supply, are instantaneously effected in the direction of 50 meeting the load demands irrespective of the steam pressure, but at the same time any change in the steam pressure, with constant steam flow, will bring about the necessary 55 adjustments of the controlling means to store predetermined normal pressure conditions, it being characteristic of the inven-

tion described herein that the mechanism controlling combustion such as the stack damper, stoking mechanism and devices controlling the feed of air, will be adjusted 60 directly or indirectly to increase combustion both by an increase in the rate of flow and a drop of static pressure while an increase of static pressure and a decrease in the rate of flow will each of them bring about a 65 reduction of combustion. The invention is hereinafter more fully described and claimed.

In the accompanying drawings forming a part of this specification, Figure 1 is a 70 view partly in section and partly in elevation showing a boiler combined with regulating apparatus adapted to the practice of the method claimed herein; Fig. 2 is a similar view illustrating apparatus for the practice of the method in connection with natural draft; Fig. 3 is a view on an enlarged scale partly in elevation and partly in section of the regulating or controlling mechanism, and Fig. 4 is a diagrammatic view 80 illustrating regulating connections when employing liquid or gaseous fuel.

In the practice of the invention suitable means are employed for regulating the damper 61 controlling the escape of products of combustion from the furnace and also for controlling the feed of fuel to the furnace, such means being operative by and in accordance with the variations in the rate of flow of steam from the boiler and by and in accordance with the working pressure of the steam. Air for combustion may be forced into the fire box or a natural draft may be used. When a forced draft is employed the rate of supply will be controlled 95 directly by and in accordance with the rate of flow of steam to the point of use and the static pressure of the steam, but when natural draft is employed, its flow to the furnace will be approximately proportional to 100 the flow of products of combustion from the furnace, and as the escape of products of combustion is controlled by the flow and pressure of steam, the supply of air under natural draft will be also, though indirectly, 105 under the control of the steam flowing from the boiler.

In the combination shown herein the stack damper 61 is connected by a cord 60 or other suitable means to a frame 29 which is connected to the piston rod of the cylinder 28. The flow of fluid pressure to the respective

ends of this cylinder is controlled by a pilot valve 25, the movable member of such valve mechanism being connected by a link to an arm extending from the rock shaft 21 mounted in a frame 20 which has a pivotal support. The frame 20 is adapted to be shifted to open the valve in the pilot mechanism by a lever 15 which is connected to one member of a double diaphragm motor of substantially the construction shown and described in an application Serial Number 254,975 filed of even date herewith. The diaphragms of the motor are arranged intermediate a cap piece 2 which is preferably integral with the bed plate 3, and a shell 4, the diaphragms being spaced a substantial distance apart by an annular block 5. The chamber above the upper diaphragm is so connected by a pipe 11 to the outlet pipe C from the boiler that there will be maintained in such chamber and operative upon the upper diaphragm a pressure equal to the static pressure of the steam plus or minus the dynamic pressure of the steam flowing through this pipe dependent upon the arrangement of the Pitot tube within the pipe C.

The chamber intermediate the diaphragms is connected by a pipe 12 to the outlet pipe C in such manner as to maintain within such intermediate chamber a static pressure equal to that of the steam flowing along the outlet pipe C. Within the shell 4 is arranged an inverted cup 13 and the shell is so filled with a fluid as to form an air space at the upper end of the cup. This body of air is maintained at a pressure substantially equal to the normal working pressure of the steam and in order to establish such pressure within the shell, the pipe 12 is connected by a valved pipe 14 with the shell and prior to the apparatus being started into operation the valves in the pipe 14 are opened while steam is flowing along the outlet pipe or pipe 12 may be connected directly to the boiler, so as to subject the air cushion in the shell to the pressure desired and when the pressure has been attained, the valves in the branch 14 are closed so that thereafter the underside of the lower diaphragm will be subjected to a yielding pressure substantially equal to the normal static pressure of the steam.

In case of a variation in the rate of flow of steam from the boiler, the upper diaphragm will be shifted in accordance with such variations, thereby through the lever 15, shifting the frame 20 to so move the pilot valve 25 as to admit steam to the upper or lower end of the cylinder 28 dependent on the direction of the change of rate of flow of steam in the outlet pipe, *i. e.*, whether the rate of flow is increased or decreased. By the movement of the pilot valve fluid pressure is admitted to the cylinder and the pis-

ton and frame 29 shifted. By this movement of the frame 29 an angularly arranged bar 32 is shifted along a shoe 33 pivotally mounted on the upper end of a swinging member 26. By the movement of the bar 70 through the shoe this swinging member is shifted which in turn will so shift the arm 23 which as before stated is on the rock shaft with the valve shifting arm 22, as to close the previously opened pilot valve and stop 75 further movement of the piston. As will be seen in Fig. 3, the swinging member has its lower end pivotally mounted on the arm of the bell crank lever 34 which has its opposite arm connected to the lever 16 adapted to be shifted by a movement of the lower diaphragm on a change of static pressure in the intermediate chamber. As the pressure in this chamber which follows that of the outflowing steam changes the lower end of the 80 swinging member 26 will be swung in or out and thereby through the link 27 shift the arm 28 and thereby open the pilot valve; on the movement of the piston in the cylinder 28 following the opening of the pilot 85 valve, the rod 32 will move through the shoe 33 and shift the upper end of the swinging member in a direction to effect a closing of the pilot valve through the link 27 and arm 23. Thus it will be seen that where the 90 rate of flow or the static pressure of the steam flowing through the outlet pipe C changes, there will be a corresponding shifting of the frame 29, but this movement will be simply incremental, the extent of movement being dependent upon the angular arrangement of the rod 32 with reference to the axis of the cylinder. As hereinbefore 95 stated, the frame 29 is connected by a cord 60 to the stack damper 61 so that the incremental movement of the frame 29 will cause a corresponding incremental movement of the stack damper, thereby permitting an increase or decrease of the rate of flow of products of combustion from the furnace. 100

The feed of fuel to the furnace is controlled by a suitable mechanism whose operation will be regulated by the movement of the frame 29, the connections extending from the frame being dependent on the character of the stoking mechanism employed. When employing a steam operated stoking mechanism 66, a roto-reciprocating valve mechanism such as described in Letters Patent No. 1,247,217, dated November 20th, 120 1917, is preferably employed. This valve mechanism consists generally stated in an external shell 67 having an annular chamber 68 connected by the pipe 69 to the cylinder of the stoking mechanism, the shell 67 125 being connected by a pipe 70, to a suitable source of supply. Within the shell is arranged an inverted cup 71 secured to a rod 72 passing through the shell and provided with ports adapted to be moved into and out of 130

register with the ports leading from the annular chamber when the cup shaped valve is shifted either longitudinally of the shell or rotated. The longitudinal movement of the valve is effected by the frame 29 operating through the lever 73 connected to the frame and to the lower end of the valve stem. The rotary movement of the valve is effected by connecting the upper end of the valve to a sleeve 74 slidable along a rod 75 carried in a frame 76 which can be adjusted to assume an angular position relative to the axis of the valve shell. As the movement of the valve of the roto-reciprocating mechanism is effected by the frame 29 it follows that the feed of fuel is controlled by and in accordance with changes in the rate of flow of steam through the pipe C and changes of pressure of the steam. As hereinbefore stated, either a forced or a natural draft may be employed for supporting combustion in the furnace as shown in Figs. 1 and 2. When a forced draft is employed, a valve or damper 64 arranged in the conduit for conducting air to the furnace is operatively connected by a cord to the frame 29 so that the admission of air also is controlled by and in accordance with changes in the rate of flow and changes in the static pressure of the steam. The movements of the stack and air duct dampers are calibrated so that the inflow of air will bear a definite relation to the discharge of products of combustion so as to maintain a substantially uniform furnace pressure.

When it is desired to employ a fluid fuel as oil or gas, the valves 77 and 78 controlling respectively the flow of fluid-fuel and steam or air to the burner 79 are suitably connected to the regulating mechanism. In the construction shown in Fig. 4, the operating handles of the valves 77 and 78 are connected to the cord 60 leading from the frame 29 of the regulating mechanism, said cord being also operatively connected to the stack damper 61.

When installing mechanisms for the practice of the invention described and claimed herein the position which the stack damper should occupy under normal working conditions is determined and the regulating mechanism is so adjusted that the predetermined or normal static pressure in the boiler will, operating through the regulating mechanism, hold the damper in such position. After such adjustment, variations in flow will cause a fluctuation of the piston of cylinder 28 from its normal position, the range of the fluctuation being proportional to the changes in the rate of flow of steam from the boiler. In case of a change in static pressure, the piston will assume another position and changes of flow will produce fluctuations of the piston relative to its new position. In other words, the field of move-

ment of the piston due to changes of flow, will be largely determined by the static pressure of the steam.

As is well known, the pressure of the steam and the rate of flow of steam from a boiler are the factors which determine the horse power developed by a boiler and hence it is characteristic of the invention described herein that regulation of combustion is effected in accordance with the horse power developed.

While the invention has been described and shown in connection with apparatus for the generation of steam, it will be apparent that the improvements can be used for controlling combustion with vapor generators generally.

In the practice of the invention described and claimed herein combustion is affected by any one of the following operations: the discharge of gases from the furnace, the feed of fuel to the furnace and the supply of air for combustion of fuel in the furnace, and provision is made for controlling each of said operations.

90

I claim as my invention:

1. The combination of a generator of vapor having a furnace with means for controlling the escape of products of combustion from the furnace of the generator, means for controlling the feed of fuel to the furnace, means for feeding air under pressure to the furnace and mechanisms operative by and in accordance with changes in the rate of flow of vapor from the generator and with changes in the static pressure of the vapor for regulating the operation of the combustion products controlling means and the fuel and air feeding means.

2. The combination of a generator of vapor having a furnace, means for controlling the escape of products of combustion from the furnace of the generator, fuel feeding means, a fluid pressure cylinder having its piston operatively connected to the damper and to the fuel feeding means, a valve mechanism for controlling the flow of fluid under pressure to said cylinder, means operative by and in accordance with changes in the rate of flow of steam from the generator for opening said valve and operative by and in accordance with changes in static pressure of the vapor for opening the valve, and means operative on a predetermined movement of the piston of said cylinder for closing the said valve.

3. The combination of a generator of vapor having a furnace, means for controlling the escape of products of combustion from the furnace of the generator, air feeding means, fuel feeding means, a fluid pressure cylinder having the piston operatively connected to the damper and to the fuel and air feeding means, a valve mechanism for controlling the flow of fluid under

- pressure to said cylinder, means operative by and in accordance with changes in the rate of flow of vapor from the generator for opening said valve and operative by and in accordance with changes in static pressure of the vapor for opening the valve and means operative on a predetermined movement of the piston of said cylinder for closing the valve.
- 10 4. The combination of a vapor generator having a furnace with means for changing the pressure of gases in the furnace and operative by and in accordance with changes in the rate of flow of vapor from the generator and by and in accordance with changes in the static pressure of vapor in the generator.
- 5 5. The combination of a vapor generator having a furnace with means for regulating the pressure of gases in the furnace, means for feeding fuel to the furnace and means operative by and in accordance with changes in each of the components forming the total pressure of vapor flowing from the generator for regulating the operation of the furnace pressure controlling means and the fuel feeding means.
- 10 6. The combination of a vapor generator having a furnace with means for controlling the discharge of gases from the furnace, means for feeding fuel to the furnace, means for supplying air to the furnace, mechanism for adjusting one of said means by and in accordance with variations of static pressure of the vapor and mechanism for changing such adjusted means by and in accordance with changes in the rate of flow of vapor from the boiler.
- 15 7. The combination of a vapor generator having a furnace with a stack damper, means operative by and in accordance with the static pressure of the vapor for adjusting the position of the damper and means operative by and in accordance with the rate of flow of vapor from the generator for shifting the damper relative to position given by the static pressure.
- 20 8. The combination of a vapor generator having a furnace, means for feeding fuel to the furnace, means operative by and in accordance with changes in the static pressure of the vapor for adjusting the operation of the fuel feeding means and means operative by and in accordance with changes in the rate of flow of vapor from the generator for varying the rate of feed of fuel as established by the static pressure.
- 25 9. The combination of a vapor generator having a furnace, means for feeding air to the furnace, means operative by and in accordance with changes in the static pressure of the vapor for adjusting the operation of the air feeding means and means operative by and in accordance with changes in the rate of flow of vapor from the generator for varying the rate of feed of air as established by the static pressure.
- 30 10. The combination of a vapor generator having a furnace with means for effecting the regulation of one of the operations affecting combustion, mechanism operative by and in accordance with the changes in the rate of flow of steam from the generator, mechanism operative by and in accordance with changes in the static pressure of steam in the generator, both of said mechanisms being adapted to operate the regulating means in the same direction on an increase in the rate of flow or a decrease in static pressure or vice versa.
- 35 In testimony whereof, I have hereunto set my hand.
- 40 JOHN M. HOPWOOD.
